CLAIM

The ornamental design for a fuel housing adapter, as shown and described.

DESCRIPTION

FIG. 1 is a top, right perspective view of the fuel housing adapter;

FIG. 2 is a bottom, right perspective view of the fuel housing adapter;

FIG. 3 is a rear elevation view of the fuel housing adapter;
FIG. 4 is a front elevation view of the fuel housing adapter;
FIG. 5 is a right side elevation view of the fuel housing adapter;

FIG. 6 is a left side elevation view of the fuel housing adapter;

FIG. 7 is a top plan view of the fuel housing adapter; and,
FIG. 8 is a bottom plan view of the fuel housing adapter.
The broken lines shown in the drawings are for the purpose of illustrating portions of the fuel housing adapter that form no part of the claimed design.
